UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A MISS'S JACKET.

SPECIFICATION forming part of Design No. 14,802, dated February 19, 1884.

Application filed November 19, 1883. Term of patent 3½ years.

To all whom it may concern:

Be it known that I, LOUISE TULLY, of the city, county, and State of New York, have invented and produced a new and original Design for a Pattern of a Miss's Jacket, numbered 8,989; and I do hereby declare that the engraved prints accompanying this specification convey to any one accustomed to using paper patterns a clear understanding of how a garment made up by the pattern will appear.

The design shows closely-fitted double-breasted fronts, each flaring in a deep point below the closing, and shortened gradually toward the back, a shorter closely-fitted back,

exhibiting under-folded plaits at the ends of its seams, and overlapped in front of the plaits by extensions of the fronts, a standing collar, and coat-sleeves.

What I claim as my invention, and desire to secure by Letters Patent, is—

The design for a miss's jacket, as shown in the engraved prints accompanying this specification.

LOUISE TULLY.
